CLAIM

The ornamental design for a bracket for multiple sonar transducer array housings, as shown and described.

DESCRIPTION

FIG. 1 is a right top perspective view of a bracket for multiple sonar transducer array housings in accordance with an embodiment of the present invention;

FIG. 2 is a front view of the bracket for multiple sonar transducer array housings of FIG. 1;

FIG. 3 is a rear view of the bracket for multiple sonar transducer array housings of FIG. 1;

FIG. 4 is a left view of the bracket for multiple sonar transducer array housings of FIG. 1;

FIG. 5 is a right view of the bracket for multiple sonar transducer array housings of FIG. 1;

FIG. 6 is a top view of the bracket for multiple sonar transducer array housings of FIG. 1;

FIG. 7 is a bottom view of the bracket for multiple sonar transducer array housings of FIG. 1;

FIG. 8 is a right top perspective view of the bracket for multiple sonar transducer array housings of FIG. 1 in an environment of use; and,

FIG. 9 is a right top perspective view of the bracket for multiple sonar transducer array housings of FIG. 1 in an environment of use.

The dash-dash broken lines illustrate environmental structure and form no part of the claimed design. The dash-dot-dash broken lines define the bounds of the claimed design and form no part thereof.
